UNITED STATES PATENT OFFICE

2,626,325

PEDAL CLAVIER SWITCH MECHANISM

Laurens Hammond, Chicago, and George H. Stephens, Glencoe, Ill., assignors to Hammond Instrument Company, Chicago, Ill., a corporation of Delaware

Application November 2, 1949, Serial No. 125,106

4 Claims. (Cl. 200—5)

1

Our invention relates generally to switch mechanisms for electrical musical instruments and more particularly to pedal operated latching switch mechanisms.

In instruments of the type shown in the patent to L. Hammond and J. M. Hanert, No. 2,480,132, it is desirable to provide pedal operated switches which, when operated by a pedal, are latched in operated position until another pedal is depressed. In this way a sustained tone may be produced without requiring the player to keep his foot on the pedal. The switch mechanism for this purpose must be reliable and quiet in operation, must be of light weight, and compact. It is therefore the primary object of our invention to provide a switch mechanism having these characteristics and which may be economically produced.

Other objects will appear from the following description, reference being had to the accompanying drawings in which:

Figure 1 is a right side elevational view of our improved pedal clavier switch mechanism, a portion of the case therefor being shown in section;

Figure 2 is a fragmentary plan view thereof;

Figure 3 is a horizontal sectional view taken on the line 3—3 of Fig. 1; and

Figures 4 and 5 are vertical sectional views taken on the lines 4—4 and 5—5 of Fig. 3.

As more fully shown in our copending application, Serial No. 11,455, filed February 27, 1948, which has matured into Patent No. 2,508,514, a pedal clavier for an instrument of the type shown in said Patent No. 2,480,132 comprises twelve pedals arranged in a manner similar to those of an organ. In Fig. 2 there are shown but two natural pedals 10 and a single sharp pedal 12, which are intended to be representative of the complete pedal clavier of twelve pedals. Each of the pedals 10 is held upwardly against a fulcrum 14 by a relatively strong coil spring 16, while each of the sharp pedals is held against its fulcrum 18 by a similar spring 20. The pedals and their supports are mounted in a supporting frame 22 which is suitably secured in the instrument case 24.

A base plate 26 and a housing 28 are suitably secured to the frame 22 by bolts 30. As best shown in Figs. 3, 4 and 5 the switch mechanism within the housing 28 is mounted between a plurality of frame plates 32 which are held in suitably spaced relation by a notched strip 38 and by a notched strip 34 which extends through elongated slots 36. A pair of wires 40 extending through the slots 36 hold the notches of the strip

2

34 in engagement with the vertical frame plates 32, while the strip 38 is held in place by a plurality of screws 42 threaded in an anchoring bar 44 which extends through suitable slots 46 formed in the plates 32. The frame plates are also secured to angles 50 and 51 by screws 52 which are threaded in anchoring plates 54 and 55. The frame plates 32 are thus rigidly and firmly joined.

10 A tubular rock shaft 56 has small diameter pins 58 secured in its ends which extend through suitable bearings 60 mounted in bearing plates 62 (Fig. 5) secured to the end frame plates 32. The shaft 56 has a plurality of bell cranks 64 secured thereto as by welding, soldering or brazing. An arm 66 is similarly secured to the shaft 56. The bell crank 64 and arm 66 are of bail-like construction for the sake of rigidity, strength and lightness. The rearwardly projecting arm 68 of each of the bell cranks 64 normally rests upon the felt padded end of a push rod 70 suitably secured to each of the pedals 10, 12. The push rods 70 extend through large openings 72, 73 in the base plate 26 and in an inverted channel 74, and slide through a sound deadening felt pad 76 which is held in place by the channel 74, the channel 74 being suitably secured to the base plate 26. The hollow shaft 56 together with all parts carried thereby is biased to swing clockwise (Fig. 4) by a tension coil spring 80 which is stretched between the arm 66 and the anchoring strip 55.

15 The upwardly extending arm of each of the bell cranks 64 has a latch operator 82 secured thereto, this operator being preferably made of a suitable sheet plastic and riveted to the arm of the bell crank 64. The operators 82 are adapted to engage leaf spring latches 84 which are secured at their lower ends to depending arms 86 of switch frames 88. The switch frames 88 are secured to the crossbar 38 by screws 90 which also clamp switch arms 92 in place, the metallic parts being separated by suitable sheets 93, 94 and 95 of insulating material. The switch arm 92 and the sheet 95 have rectangular openings 96 and 97 respectively through which the depending arm 86 extends. The forward crosspiece portion of the sheet 95 serves as a stop to limit forward flexure of its associated leaf spring latch 84. The forward crosspiece of the arm 92 has a short length of contact wire 98 welded thereto for engagement with three complementary contact wires 99 which are welded beneath the trifurcated end portions of flexible, resilient switch arms 100. These switch arms are secured to the forward end cross-

piece portion of the switch frames 88 by bolts 102, which also clamp a reinforcing leaf spring 104 in place beneath each of the switch arms 100. The outer end of each spring 104 engages a switch actuator 106 which is a strip of insulating sheet plastic and which is guided for substantially vertical movement in slots formed in the notched strip 34 and in the base plate 26. The lower end of each of the actuators 106 extends through the space between the shaft 56 and the bail portion of its associated bell crank 64, through a slot in the base plate 26, and is held in contact with one of the keys 10 or 11 by the leaf spring 104. By this means the actuator 106 is held in position so that it will not vibrate or rattle. It will be understood that it is desirable to have some lost motion of the actuator 106 relative to the leaf spring contact finger or arm 100 to allow for unavoidable discrepancies in the dimensions of the various parts of the mechanism. However, such lost motion would result in noisy operation if the leaf spring 104 were not provided.

The movement of the rearward ends of the keys 10 is limited by a felt upstop 110 and a felt downstop 112 which are suitably held in place by shouldered studs 30. Counterclockwise swinging movement of the rock shaft 56 is limited by the engagement of the arm 66 with a felt pad 114 which is secured to a fixed bracket 116.

As best shown in Fig. 5, a bushing 118 is secured to the right-hand pivot 58 of the rock shaft 56 and this bushing has a radially extending switch operator 120 fixed thereto. An angle bracket 121 is secured to the right-hand frame plate 32 by screws 122 which also serve to attach the bearing plate 62 to the frame plate. A pair of insulating supports 124, 125 are riveted to the horizontal portion of the bracket 121. A flexible bifurcated switch arm 126 is riveted to the support 124 while a rigid switch member 128 is riveted to the insulating support 125. The member 128 and the bifurcated ends of switch arm 126 have cross wires 130 of suitable contact alloy welded thereto respectively.

Whenever one of the pedals is depressed, its push rod 70 will engage the horizontal arm 68 of its associated bell crank 64 and swing the latter, and the rock shaft 56, counterclockwise to substantially the dotted line positions shown in Fig. 4. At the same time the actuator 106 will flex the leaf spring 104 upwardly until it engages the resilient switch arm 100 raising the latter from contact with the switch arm 92. At the same time operators 82 of all the bell cranks 64 will engage their associated latch springs 84, flexing them to the dotted line position shown in Fig. 4. Upon releasing the depressed pedal, the rock shaft will be rotated in clockwise direction by the spring 80 and operators 82 will swing away from the latch springs 84. The latch spring 84 associated with the key which was depressed will engage beneath the end of the resilient switch arm 100 associated therewith and hold the latter in the position in which it is shown in full lines in Fig. 4. The latch springs 84 associated with the other keys will abut against the ends of their associated switch arms 100 since the latter will not have been flexed upwardly but instead will be in contact making position. The relationship of the parts is such that the latch springs 84 will be permitted to swing into latching position before the actuator 106 has moved downwardly a sufficient distance to permit the ends of the switch arm 100 to interfere with the operation of the latch. The switch arm which is latched in the

open position, as shown in full lines in Fig. 4, will of course be released and permitted to move to contact making position immediately upon depression of another pedal.

5 Whenever any of the pedals is depressed the rock shaft is swung counterclockwise as shown in Fig. 5 so as to permit the switch arm 126 to flex downwardly and make contact with the switch member 128.

10 The fact that each of the switch arms 100 is trifurcated and is provided with three contact wires 99, enormously reduces the possibility that the switch might fail to make contact due to the presence of dust or dirt. Similarly the fact that the switch arm 126 is bifurcated greatly reduces the possibility of failure to make contact.

15 The parts of the mechanism are mechanically strong but nevertheless light in weight. They therefore have little inertia, and may be operated rapidly without producing objectionable noises.

20 While we have shown and described a particular embodiment of our invention, it will be apparent to those skilled in the art that numerous modifications and variations may be made in the 25 form and construction thereof, without departing from the more fundamental principles of the invention. We therefore desire, by the following claims, to include within the scope of our invention all such similar and modified forms of the apparatus disclosed, by which substantially the results of the invention may be obtained by substantially the same or equivalent means.

We claim:

1. In a switch mechanism for a pedal clavier comprising a plurality of pedals, a rock shaft, a plurality of bell cranks secured to the rock shaft and each having an arm thereof forming a unidirectional driving connection between one of the pedals and the shaft, a spring to rotate the shaft in a direction opposite to that in which it may be rotated by the depression of a pedal, a switch including a resilient arm for each pedal, an actuator and a spring forming a resilient lost-motion connection between each pedal and its associated switch arm, a resilient latch for each switch to hold it in operated condition, means on the other arm of each bell crank to release its associated latch, and means forming part of each switch for preventing operation of its associated latch.

45 2. A switch mechanism for the pedal clavier of an electrically controlled musical instrument comprising reciprocable switch actuators for operation by the clavier pedals respectively, a switch for each of the pedals for operation by the associated actuator, each switch comprising a long and a short rigid hollow rectangular frame, the long frame having an arm integral therewith and depending freely through the opening in the short frame, means including insulating plates for holding the frames in insulated spaced relation, a flexible switch arm secured to the long frame with parts thereof in alignment with the opening in the short frame and arranged to make contact with the short frame, and a leaf spring latch secured at its lower end to the lower end of the depending arm and having its upper end extending through the opening in the short frame and held from contact with the latter and in position beneath the end of the flexible switch arm by one of the insulating plates.

60 3. The combination set forth in claim 2 in which the contact making end of the flexible switch arm is divided into a plurality of contact making fingers, and in which each of the fingers has a short length of contact wire welded thereto.

4. In an electrical musical instrument having a plurality of pedals, a plurality of switches, one for each pedal and each including a resilient flexible switch arm, a resilient latch for each switch arm effective to hold the switch in operated position, means operated by the depression of any of the pedals to move all of the latches out of the paths of the switch arms and to permit all of the latches to move into the paths of movement of the switch arms during the early part of the return stroke of the pedal, a switch operator for each pedal for transmitting motion from the pedal to the switch arm, and a spring for each operator normally holding the operator a short distance away from the switch arm so as to provide some

5

lost motion of the operator relative to its switch arm during the initial portion of the downward stroke of its pedal.
